David Wilson, of. Thunon, State of Vermont.

Letters. Patent.

The schedule referred to in these Letters Patent, and making part of the same, containing a description in the words of the said David Wilson, himself, of his improvement in his machine for winnowing grain.

Be it known that David Wilson of Thunon in the County of Franklin and State of Vermont, has made a new and useful improvement in the winnowing Machine, which is described as follows, reference being had to the annexed drawing of the same, making part of this specification. The Machine consists of a frame α , made similar to the form of a common winnowing machine, open at one end and enclosed at the other end by a curved back β , of thin boards, forming a seat the back being also divided by a similar board, within this frame the scales C , tray D , and screen E , are suspended by springs in an inclined position, the inclination of the screen being in an opposite direction to that of the sieve, and vibrating horizontally, a vertical shaft $\mathfrak{a}$ is placed in the centre of the seat having tongs or jaws F fastened to it, and a cast iron spur wheel G on its upper end, a small crank H is attached to the end of the shaft to which crank is attached a connecting rod I leading to the shoe K , to which it is attached for giving the horizontal vibratory motion to the shoe, a crown wheel L looks into the spur wheel which crown wheel is placed upon a horizontal shaft $\mathfrak{a}$, on the top of the frame, a hopper of the usual construction is placed above the shoe, an inclined board M is placed below the shoe to convey the cleaned grain to a receiver, there are two other inclined boards N & P for the purpose of separating the chaff from the chaff.

170 9435
and also from the foul seed, which passes through the screen, the grain being put into the hopper motion is given to the machine by a curved lever on the end of the horizontal shaft which gives motion to the vertical shaft, with the fan, also to the vibrating rod or shaking staff, which gives motion to the sieve, screen &c. the grain to be screened passing down from the hopper upon the shaking sieve, and when grain is thus separated, from the chaff and dust by the motion of the sieve produced by the current of air caused by the fan, what I claim as my invention and which I desire to secure by Letters Patent consists in the arrangement and adaptation of the several parts of the before described horizontal winnowing machine.
